Inventor:

Parker H. Sweet, Jr.

UNITED STATES PATENT OFFICE.

PARKER H. SWEET, JR., OF WASHINGTON, D. C., ASSIGNOR TO THE HEATON
BUTTON FASTENER COMPANY, OF PROVIDENCE, R. I.

BUTTON-FASTENER.

SPECIFICATION forming part of Letters Patent No. 323,465, dated August 4, 1885.

Application filed December 22, 1884. (No model.)

To all whom it may concern:

Be it known that I, PARKER H. SWEET, Jr., a citizen of the United States, residing at Washington, in the District of Columbia, have 5 invented certain new and useful Improvements in Button-Fasteners; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My present invention has for its object to 15 provide an improved and simplified metallic fastener for attaching buttons to fabrics or other materials; and it consists, essentially, in forming the said fastener from a metallic staple, which is bent in such a manner as to 20 provide a central loop or neck portion, a flat table or wings upon two sides of said central loop, and two sharp-pointed fastening-prongs projecting downward at right angles to said wings, all as will be hereinafter fully described, 25 and specifically designated in the claims.

In the accompanying drawings, Figure 1 represents a plan view of the blank or staple from which my improved fastener is formed; Fig. 2, a perspective view of the complete 30 fastener; Fig. 3, a similar view showing the attachment of the fastener to a button and fabric, and Fig. 4 a side view thereof.

Similar letters of reference occurring on the several figures indicate like parts.

In carrying out my invention the metallic staple A is preferably cut from suitable sheets 35 of metal, although it may be formed from round or flat wire, if deemed desirable. In constructing the complete fastener the upper 40 central portion of the staple A is first bent up into a loop or neck, a, in such manner as to provide a wing or table, b, upon each side of the said loop or neck a and in parallel lines therewith, the said wings or table terminating in two sharp-pointed prongs, c, which 45 are bent downwardly in parallel lines to each other and the loop or neck a, and at right angles to the side wings or table, b, as fully shown in Fig. 2.

50 In the operation of attaching a button to a

fabric or other material by means of my improved fastener the shank of the button is passed over one of the prongs c and side wing, b, into the central loop, a, and the two parts thus connected together are then adjusted in 55 the upper jaw of an improved setting-instrument, which forms the subject of a separate application for patent filed by me of even date herewith, being Serial No. 150,962, and the two jaws of the said setting-instrument 60 being closed together upon the fabric or material forces the prongs of the fastener through the same, and by means of a die in the lower jaw curves or deflects the points of said prongs back into the under surfaces of the said 65 material in such manner as to securely clamp the same between the prongs and the side wings or table, b, as fully shown in Fig. 4. The loop or neck a of the fastener being arranged in parallel lines with the side wings, 70 b, and prongs c, enables the button to be set in such a position upon the fabric or material that the shank of the same comes in a line parallel with the length of the button-hole, instead of crosswise or transversely, as is the 75 case with fasteners of a kindred nature which are objectionable in that they spread and twist the button-hole out of shape, a defect which my improvement entirely overcomes.

By means of my invention I am enabled to 80 provide an efficient and durable fastener capable of being readily attached to a button and fabric in the most secure manner, and which can be produced at a reduced cost.

Having thus described my invention, what 85 I claim as new and useful is—

As an improved article of manufacture, the herein-described button-fastener, consisting of the central loop, a, side wings or table, b, and two downwardly-projecting prongs, c, the said 90 loop, side wings, and prongs being arranged in lines parallel with each other, and adapted for operation substantially as and for the purpose specified.

In testimony whereof I affix my signature 95 in presence of two witnesses.

PARKER H. SWEET, JR.
